UNITED STATES PATENT OFFICE.

ALBERT G. BELLAIRE, OF DETROIT, MICHIGAN.

FEED-FINGER FOR AUTOMATIC SCREW-MACHINES.

1,142,660.

Specification of Letters Patent.

Patented June 8, 1915.

Application filed March 31, 1914. Serial No. 828,508.

To all whom it may concern:

Be it known that I, ALBERT G. BELLAIRE, a citizen of the Dominion of Canada, residing at Detroit, in the county of Wayne and State 5 of Michigan, have invented new and useful Improvements in Feed-Fingers for Automatic Screw-Machines, of which the following is a specification.

The invention relates to a feed finger for 10 automatic screw machines comprehending a structure which will accurately fit stock of any sectional contour.

The main object of the present invention is the provision of a feed finger including 15 slotted sleeve tapered at the ends to permit a centralizing of the stock and provided with a series of loose gripping dogs adapted to effectively grip the stock during feeding operation.

20 The invention in the preferred form of details will be described in the following specification, reference being had particularly to the accompanying drawings, in which:—

25 Figure 1 is a view in elevation of the improved feed finger. Fig. 2 is a section on line 4—4 of Fig. 3. Fig. 3 is a vertical sectional view, showing the improved feed finger within control sleeve. Fig. 4 is a perspective view of one of the dogs. Fig. 5 is a 30 broken sectional view illustrating the application of the improvement.

Referring particularly to the accompanying drawings, the improved feeder is designed 35 to fit within the ordinary automatic feed finger of a screw machine, and in the embodiment presented by my invention includes a sleeve like member 1 of uniform bore throughout and having the ends of said 40 bore outwardly flaring at 2. The sleeve is formed with longitudinally disposed slots 3 terminating at their forward ends immediately adjacent the forward end of the sleeve. The end walls of the slots are down- 45 wardly or inwardly convergent, and dogs 4 are arranged to seat in said slots to engage

the material. The dogs are rectangular in cross section, have their ends inclined to conform to the convergent walls of the slot and their inner gripping edges of slightly 50 depressed curvature.

The feeder is adapted to fit within the feed sleeve 5, which sleeve is longitudinally slotted at 6 the slots extending through the forward end of the sleeve to present spaced 55 spring sections 7.

In use, the material is gripped between the dogs and locked in such position from the pressure of the stock as to bind the sleeve on the box. The feed fingers stay in the 60 same position from the time the stock is put into it until the bar of stock runs out. The feeder is screwed into a cone and the feed arm controls the cone, feed finger and sleeve combined. The sleeve, feeder, cone and 65 stock all revolve at the same time so that the springs remain always on the dogs. When the stock is fed into the chuck, the latter grips the stock and the feeder slides back to its regular starting place. 70

What is claimed is:—

1. A feeder for screw machines including a sleeve having closed end slots formed longitudinally therein, the end walls of the slots being inwardly convergent, and dogs having 75 correspondingly inclined ends and slidably fitted in the slots, and means for yieldingly holding the dogs inward of the sleeve.

2. A feeder for screw machines including a sleeve having closed end slots formed longitudinally therein, the end walls of the slots being inwardly convergent, and dogs having correspondingly inclined ends and slidably fitted in the slots, the ends of the sleeve being outwardly flaring, and means for yieldingly holding the dogs inward of the sleeve. 80 85

In testimony whereof I affix my signature in presence of two witnesses.

ALBERT G. BELLAIRE.
